UNITED STATES PATENT OFFICE

JOHN ZILLIOX, OF ORCHARD PARK, NEW YORK

WRENCH

Application filed March 7, 1928. Serial No. 259,654.

This invention relates to a wrench and more particularly to an open end machine end wrench in which a plurality of open end machine wrench heads having different sized jaws are employed in connection with the same handle thereby greatly decreasing the cost of a set of such wrenches as well as permitting of a compact and convenient kit.

One of the objects of this invention is to provide such a handle and open end machine wrench heads therefor in which the heads can be quickly applied to or removed from the handle and when so applied are securely held to the handle and operate reliably to permit the desired pressure to be applied to the object gripped.

A further object is to provide such an open end machine wrench which is strong and which will stand up under the severe and constant use to which tools of this character are subjected.

A still further aim is to provide such an open end machine wrench which is simple and inexpensive and in which all of the more expensive manufacturing operations are performed on the handle since only one handle is used in connection with a large number of heads.

Another aim is to provide an open end machine wrench of this character in which the head can be held in different positions relative to the handle thereby permitting of its use in places where an open end machine wrench having a head set at a fixed angle could not be employed, and in which such adjustment in the angularity of the head can be effected expeditiously and be reliably held.

Other objects are to provide such an open end machine wrench which is compact, light and strong, thereby permitting of its convenient use by the mechanic.

In the accompanying drawings:—

Figure 1 is a top plan view of the preferred embodiment of my invention. Figure 2 is a side view thereof. Figure 3 is a longitudinal section thereof. Figure 4 is a fragmentary bottom plan view thereof. Figure 5 is a fragmentary bottom plan view of a modified form of the invention.

Similar reference numerals refer to like parts in each of the several views.

The preferred embodiment of my invention shown in Figs. 1—4 is constructed as follows:

The wrench is composed of a handle 15 to one side and at one end of which the open end machine wrench head 16 is applied. The wrench handle 15 may be of any suitable construction and preferably is hollowed out on its opposite sides for lightness and is provided with a hole or opening 17 at one end so that it can be hung up when not in use.

The opposite end 18 of the wrench is formed to provide a flat face 19 on its underside which face is engaged by the upper flat face of the open end machine wrench head 16. This face is preferably set at an angle to the handle so that the head is held at a similar angle for convenience in manipulating the wrench.

The wrench head 16 comprises a pair of jaws 20 and a shank or neck 21 which is provided with a circular opening or recess 22 which extends therethrough and receives a cylindrical stem 23 which stem projects downwardly from the flat face 19 and is formed integrally with the handle. The engagement of this stem in the opening 22 holds the head to the stem and to prevent the head from accidentally dropping off friction means are provided which are constructed as follows:

On the underside of the handle in rear of the flat face 19 a transverse ridge 24 is provided which engages the rear end of the neck or shank 21 of the wrench head and also houses a spring loaded pin 25 which bears against the rear end or edge of the wrench head and thereby tends to prevent it from being moved laterally except when pressure is intentionally applied to the head to remove it from the handle. This ridge, as best shown in Fig. 4 is formed at its outer edge to provide a flat vertical face or shoulder 26 in the center of which a V-shaped notch 27 is provided.

To permit of different angular adjustments of the wrench head, the shank 21 of the same is formed to provide three angular faces or

shoulders 28, 29 and 30 at its sides and rear end, any of which faces can be engaged by the flat shoulder 26 on the ridge 24. By this means the head can be set at three different angles to the wrench. In addition to this either of the corners on the wrench shank 21 between the three angular shoulders or faces 28, 29 and 30 can be engaged in the central V-shaped notch provided in the ridge 24 as shown by full lines in Fig. 4. By this means two additional adjustments of the wrench head relative to the handle are provided thereby providing five different adjustments for the same. In using the wrench it is merely necessary to slip the head over the stem at the desired angle and it will be securely held thereon until it is desired to substitute the head when it may be removed laterally and another substituted.

20 The form shown in Fig. 5 is similar to the preferred form except that the spring loaded friction pins are provided in the stem 23 and bear outwardly against the bore of the opening 22 in the head. Two spring pins 31 are provided in this construction and are forced outwardly by an interposed spring 32. This form is available for larger sized wrenches where the size of the stem permits of housing the spring loaded pins.

30 Each form of my invention provides an open end machine wrench which is compact, light and durable, the wrench head is easily applied and may be adjusted to the desired angularity and when so applied is securely held against accidental displacement but is readily removed; and the wrench and particularly the wrench heads can be produced at low cost, thereby permitting of marketing the wrench for a low price.

40 I claim as my invention:

A wrench comprising a handle, a stem projecting laterally from one side of said handle, an open end wrench head having jaws and a shank, said shank being provided with an opening adapted to fit said stem and said shank being formed on its outer side to provide at least three flat faces arranged at an angle to one another and forming pointed projections, and a ridge formed on said handle adjacent the outer side of said shank, said ridge being formed to provide a flat face opposing said shank and adapted to engage any of said faces on said shank and said ridge being formed to provide a V-shaped notch at the center of its flat face, said notch being adapted to receive any one of the pointed projections on said wrench head.

In testimony whereof I hereby affix my signature.

JOHN ZILLIOX.
